HERBERT R. WHITE, OF LOWELL, MASSACHUSETTS, ASSIGNOR TO WYCKOFF, SEAMANS & BENEDICT, OF ILION, NEW YORK, A CORPORATION OF NEW YORK.

TYPE-WRITING MACHINE.

No. 878,846.

Specification of Letters Patent.

Patented Feb. 11, 1908.

Application filed November 1, 1906. Serial No. 341,595.

To all whom it may concern:

Be it known that HERBERT R. WHITE, a citizen of the United States, and resident of Lowell, in the county of Middlesex and State 5 of Massachusetts, have invented certain new and useful Improvements in Type-Writing Machines, of which the following is a specification.

My invention relates to typewriting machines and more particularly to means for effecting a fractional line spacing of the platen.

One object of my invention is to provide a simple and efficient fractional line spacing 15 device that can be readily applied to different styles of typewriting machines.

A further object of my invention is to provide a fractional line spacing device particularly adapted for positioning the platen so as 20 to write just above or just below a line as when an operator is writing exponents or fractions.

To the above and other ends which will hereinafter appear, my invention consists in 25 the features of construction, arrangements of parts and combinations of devices set forth in the following specification and particularly pointed out in the claims.

In the drawings, Figure 1 is a top plan 30 view showing the platen frame and platen of a No. 6 Remington typewriting machine with my attachments or devices applied thereto. Fig. 2 is a left-hand end view of the same with the finger wheel sectioned away. Fig. 35 3 is a fragmentary front elevation showing the parts at the left-hand end portion of the platen. Fig. 4 is a detail perspective view of a guide plate to be hereinafter more fully described.

40 I have shown my invention applied to a No. 6 Remington machine, but it should be understood that it may be employed on other styles of typewriting machines. The rectangular platen frame is made up of end bars 1, a rear cross bar 2 and a front cross bar 3. The platen 4 is mounted on a platen shaft 5 journaled in bearings in the end bars 1 of the platen frame. The shaft carries the usual finger wheels 6 at the ends thereof. 45 Secured to the platen at the right-hand end thereof is the usual line spacing ratchet wheel 7 with which a line spacing pawl 8 co-operates, said pawl being actuated by the usual means, such as those employed, for instance, in a 50 No. 6 Remington typewriting machine. A

detent roller 9 is carried at the free end of a leaf spring 10 secured at its rear end to the platen frame. The detent roller bears in the usual manner against the teeth of the line spacing wheel and tends to position the 60 platen at the regular line spacing positions by pressing between the teeth of the ratchet wheel.

In addition to the usual line spacing mechanism provided at the right-hand end of the 65 platen, I employ a toothed wheel 11 which is secured to the platen at the left-hand end thereof and is provided with crown teeth 12. A guide plate, which is designated as a whole by the reference numeral 13, is in the nature 70 of a sheet metal bracket plate secured by screws 14 to the left-hand end bar 1 of the platen frame, said bracket plate extending over the platen shaft and projecting inwardly towards the platen. This plate is provided 75 with a slot 15 which extends transversely of the platen and with a short slot 16 which extends longitudinally of the platen, one of these slots opening into the other, as clearly shown in Fig. 4.

80 The slot 16 is in the nature of a notch in one wall of the slot 15. The slot 15 is formed in part by striking up ears or lugs 17 from the body of the metal from which the guide plate is formed. These ears are tapped to receive 85 screw stops 18 for purposes which will hereinafter appear. A so-called carrier or sleeve 19 surrounds the platen shaft and is received between the wheel 11 and a sleeve or collar 20 secured to the platen shaft by a set screw 90 21 which passes into a threaded opening in the collar 20 and bears at its inner end against the platen shaft. The carrier 19 is loosely mounted on the platen shaft so that it is free to rotate around the axis of the platen as a 95 center. A pawl or engaging member 22 is pivoted at 23 to the carrier 19 to move around its pivot 23 in the general direction of the length of the platen. This pawl has an engaging nose or face 24 which is adapted to 100 be received in the spaces between the teeth 12 of the wheel 11 by swinging the pawl or engaging member to the right. The upper end 25 of the pawl constitutes a finger piece by which the pawl may be manipulated. 105 The pawl or engaging member 22 passes through the opening in the guide plate formed by the slots 15 and 16 and the construction and arrangement of the parts is such that when the pawl is contained within 110

the slot 16 it is centered between the two screw stops 18 and is out of engagement with the teeth of the wheel 11, as shown in Figs. 1 and 3. When, however, the pawl is moved 5 to the right and is in engagement with the teeth of the wheel 11 the pawl is situated in the slot 15 which extends at right angles to the slot 16. If at this time the pawl is given a movement in either direction at right angles 10 to the plane of its movement which carries it into engagement with the teeth of the wheel 11, and the platen which is connected therewith, will be given a rotation for a predetermined distance, the extent of 15 rotation depending on the adjustment of the screw stops 18. The teeth 12 of the wheel 11 are preferably of the same number as the teeth of the line spacing ratchet wheel 7 and the relative arrangement between the two sets of 20 teeth and the pawl 22 is such that when the detent roller 9 is properly seated between two teeth of the line spacing ratchet wheel, an opening between two of the teeth 12 will be brought opposite the engaging portion 24 of 25 the pawl 22, as shown in Fig. 1, so that a movement of the pawl to the right will bring it into engagement between two teeth of the wheel 11 and a rotary movement of the pawl, either backward or forward, will produce a fractional 30 spacing of the platen less than the distance between two teeth of the line spacing ratchet wheel 7 in order to move the platen so that a character may be written above or below a line determined by the teeth of the line spacing 35 ratchet wheel 7, and its spring detent 9. Thus if the pawl is turned towards the rear of the machine writing may be produced below the line, whereas if the engaging device or pawl 22 is turned forwardly to effect a 40 slight backward rotation of the platen then an exponent degree mark or other character may be written above the line. When the platen is moved by what I have termed the fractional line spacing mechanism, either 45 backwardly or forwardly against the pressure of the spring detent, it is held by the operator in this position until the character or characters to appear above or below the line are written, when pressure upon the member 22 50 is released and the spring detent 9—10 will restore the platen to its regular printing line position from which it was moved by the fractional line spacing device. In this position the member 22 will be brought opposite 55 the slot 16, and it may be moved into said slot to effect a disengagement of said member from the toothed wheel 11 when the platen is free to be operated in the usual manner by the regular line spacing mechanism. 60 It will be understood that an adjustment of the screw stops 18 will regulate the extent of backward or forward movement of the platen through an actuation of the pawl 22, and that the positions of said screw stops may 65 be varied according to the work to be produced

or the distance above and below a line where it is desired to have the characters appear.

It will be understood that when the pawl 22 is contained within the slot 15 and is at either side of the slot 16 it cannot be disengaged from the teeth of the wheel 11 until the platen is restored to its regular printing line position where the pawl 22 will be opposite the slot 16. 70

From the foregoing description it will be 75 seen that the pawl or engaging member 22 has two movements in planes which are at right angles to each other, one being a rotary movement around the axis of the platen and the other being a movement around its pivot 80 23 in the general direction of the length of the platen. 85

It will also be seen that I have provided a simple and efficient device that may be readily applied to different styles of typewriting machines and which is operative to properly position the platen with mechanical accuracy for writing above and below a line of writing. 90

Various changes may be made without departing from the spirit and scope of my invention. 95

What I claim as new and desire to secure by Letters Patent, is:—

1. In a typewriting machine, the combination of a platen, line spacing mechanism, and 95 means for writing above and below a line determined by said line spacing mechanism, said means comprising a toothed wheel connected with the platen, and a hand actuated pawl coöperative with said toothed wheel to turn it in either direction a predetermined extent. 100

2. In a typewriting machine, the combination of a platen, line spacing mechanism, means for writing above and below a line determined by said line spacing mechanism, 105 said means comprising a toothed wheel connected with the platen, and a hand actuated pawl coöperative with said toothed wheel to turn it in either direction a predetermined extent; and means for centering said pawl when it is out of engagement with said toothed wheel. 110

3. In a typewriting machine, the combination of a platen, line spacing mechanism, and 115 means for writing above or below a line determined by said line spacing mechanism, said means comprising a toothed wheel connected with the platen, a hand actuated pawl coöperative with said toothed wheel to turn it a predetermined extent, and adjustable means for determining the extent to which the wheel may be turned by said pawl. 120

4. In a typewriting machine, the combination of a platen, line spacing mechanism, and 125 means for writing above and below a line determined by said line spacing mechanism, said means comprising a toothed wheel connected with the platen, a hand actuated pawl coöperative with said toothed wheel to turn 130

it in either direction a predetermined extent, and adjustable means for determining the extent to which the wheel may be turned by said pawl.

5. In a typewriting machine, the combination of a platen, line spacing mechanism, and means for writing above and below a line determined by said line spacing mechanism, said means comprising a toothed wheel connected with the platen, a carrier pivoted to turn around the axis of the platen a predetermined extent, and a pawl pivoted to said carrier and adapted to be thrown into and out of engagement with said toothed wheel and to turn the carrier, toothed wheel and platen a predetermined extent in either direction.

6. In a typewriting machine, the combination of a platen, line spacing mechanism, and means for writing above or below a line determined by said line spacing mechanism, said means comprising a toothed wheel connected with the platen, a carrier pivoted to turn around the axis of the platen a predetermined extent, a pawl pivoted to said carrier and adapted to be thrown into and out of engagement with said toothed wheel and to turn the carrier, toothed wheel and platen a predetermined extent, and a fixed guide in which said pawl works.

7. In a typewriting machine, the combination of a platen, line spacing mechanism, and means for writing above or below a line determined by said line spacing mechanism, said means comprising a fixed guide, and an engaging device pivoted to move in said guide in planes at right angles to each other, the movement of said engaging device in one plane carrying the device into and out of coöperative relation with the platen and the movement of said device in the other plane causing a rotation of the platen for a predetermined extent.

8. In a typewriting machine, the combination of a platen, line spacing mechanism, and means for writing above or below a line determined by said line spacing mechanism, said means comprising a fixed guide with slots therein at right angles to each other, and a hand actuated engaging device working in said slots.

9. In a typewriting machine, the combination of a platen, line spacing mechanism, and means for writing above or below a line determined by said line spacing mechanism, said means comprising a fixed guide with slots therein at right angles to each other, and a hand actuated engaging device working in said slots, the movement of the engaging device in one slot carrying the device into and out of operative engagement with the platen and out of and into said last mentioned slot and the movement of the engaging device in the other slot determining the ex-

tent of rotation which may be given the platen by said device.

10. In a typewriting machine, the combination of a platen, a line spacing ratchet wheel, line spacing means coöperating therewith, a toothed wheel connected with the platen and having the same number of teeth as the line spacing ratchet wheel, and an engaging device operative to engage the toothed wheel and to move the platen through a predetermined extent in either direction.

11. In a typewriting machine, the combination of a platen, a line spacing ratchet wheel, line spacing means coöperating therewith, a toothed wheel connected with the platen and having the same number of teeth as the line spacing ratchet wheel, an engaging device operative to engage the toothed wheel and to move the platen through a predetermined extent in either direction, and a fixed guide having a notch therein for centering the pawl when the latter is out of engagement with said toothed wheel.

12. In a typewriting machine, the combination of a platen, a line spacing ratchet wheel, line spacing means coöperating therewith, a toothed wheel connected with the platen and having the same number of teeth as the line spacing ratchet wheel, and an engaging device pivoted to turn in two planes at right angles to each other, the movement of said device in one plane carrying the device into or out of engagement with said toothed wheel, and the movement of said device in the other plane turning the platen through said toothed wheel a predetermined extent in either direction.

13. In a typewriting machine, the combination of a platen, a line spacing ratchet wheel, line spacing means coöperating therewith, a wheel connected with the platen and having the same number of teeth as the line spacing ratchet wheel, an engaging device pivoted to turn in two planes at right angles to each other, the movement of said device in one plane carrying the device into or out of engagement with said toothed wheel, and the movement of said device in the other plane turning the platen through said toothed wheel a predetermined extent, and adjustable means for limiting the movement of the engaging device in the last mentioned plane.

14. In a typewriting machine, the combination of a platen, line spacing mechanism, and means independent of the line spacing mechanism for turning the platen, said means comprising a toothed wheel, and an engaging device which is moved in one direction by hand into and out of engagement with said toothed wheel and which turns the toothed wheel and platen a predetermined distance at each operation.

15. In a typewriting machine, the combination of a platen; line spacing mechanism

- comprising a line spacing ratchet wheel, and a coöperative line spacing device; and fractional spacing means independent of the line spacing mechanism for writing above and below a line determined by said line spacing mechanism, said fractional spacing mechanism comprising a toothed wheel connected with the platen, an engaging device pivoted to move longitudinally of the platen and around the axis thereof, a slotted guide in which said engaging device moves, the movement of the engaging device longitudinally of the platen carrying it into and out of co-operation with said toothed wheel and the movement of the engaging device around the axis of the platen turning the toothed wheel and platen therewith for a predetermined extent to write above or below the line determined by the line spacing mechanism.
16. In a typewriting machine, the combination of a platen, line spacing mechanism comprising a line spacing ratchet wheel and a coöperative line spacing device, and fractional spacing means independent of the line spacing mechanism for writing above and

below a line determined by said line spacing mechanism, said fractional spacing mechanism comprising a toothed wheel connected with the platen, an engaging device pivoted to move longitudinally of the platen and around the axis thereof, a slotted guide in which said engaging device moves, the movement of the engaging device longitudinally of the platen carrying it into and out of co-operation with said toothed wheel and the movement of the engaging device around the axis of the platen turning the toothed wheel and platen therewith for a predetermined extent for writing above or below the line determined by the line spacing mechanism.

Signed at Lowell, in the county of Middlesex and State of Massachusetts, this twenty-ninth day of October A. D. 1906.
